US0D1051683S

(12) **United States Design Patent** (10) **Patent No.:** **US D1,051,683 S**
(45) **Date of Patent:** **** Nov. 19, 2024**

(54) **PAWL FOR A FENCING STRAINER**

(71) Applicant: **WIREMAN PTY LIMITED**, Milsons Point (AU)

(72) Inventor: **Ian Lowrey**, Redfern (AU)

(73) Assignee: **WIREMAN PTY LIMITED** (AU)

(**) Term: **15 Years**

(21) Appl. No.: **29/847,407**

(22) Filed: **Jul. 25, 2022**

(30) **Foreign Application Priority Data**

Jan. 27, 2022 (AU) 202210504

(51) **LOC (14) Cl.** **08-05**

(52) **U.S. Cl.** **D8/44**

(58) **Field of Classification Search**

USPC D8/44, 354

CPC B21F 9/00; B21F 9/002; F16G 11/12

See application file for complete search history.
